UNITED STATES PATENT OFFICE.

CHARLES FRANCIS HUNTOON, OF CHICAGO, ILLINOIS, ASSIGNOR TO
CHICAGO RAILWAY EQUIPMENT COMPANY, OF CHICAGO, ILLINOIS, A CORPORATION OF ILLINOIS.

BRAKE-BEAM.

No. 813,705.

Specification of Letters Patent.

Patented Feb. 27, 1908.

Application filed July 18, 1905. Serial No. 270,173.

To all whom it may concern:

Be it known that I, CHARLES FRANCIS HUNTOON, a citizen of the United States, residing at Chicago, Illinois, have invented a certain new and useful Improvement in Brake-Beams, of which the following is a full, clear, and exact description, such as will enable others skilled in the art to which it appertains to make and use the same, reference being had to the accompanying drawings, forming part of this specification, in which—

Figure 1 is a rear elevational view of my improved brake-beam. Fig. 2 is a sectional view on line 2 2, Fig. 1. Fig. 3 is an end elevational view of a modified form. Fig. 4 is a rear elevational view of the form shown in Fig. 3. Fig. 5 is a rear elevational view of another modified form; and Fig. 6 is a sectional view on line 6 6, Fig. 5.

20 This invention relates to a new and useful improvement in brake-beams, the object being to enable the brake-heads to be readily and quickly removed in making repairs without necessitating the unhanging of the beam or the disturbance of the integrity of the truss.

With this object in view the invention consists in the novel construction, arrangement, and combination of the several parts, all as will hereinafter be described and afterward pointed out in the claims.

In the drawings, 1 indicates the compression member of the brake-beam, and 2 the tension member.

3 indicates a thrust-block in which the end 35 of the compression member is seated and through which the tension-rod passes, the latter having a nut 4 on its end for tightening the same and placing a camber in the compression member. The front face of this 40 thrust-block is preferably flat, and its top and bottom faces are shaped to receive flanges on the brake-head 5, as shown in Fig. 2. A tapered opening is formed in the forward portion of the thrust-block, through 45 which passes a wedge-key 6, said wedge-key passing through aligning openings in rearwardly-extending flanges on the brake-head. The tendency of this wedge-key in service is to work down in its seat, thus serving to hold 50 the parts tight at all times. The top and bottom faces of the thrust-block are also inclined, so that any downward movement of

the wedge-key will tend to seat the brake-head more firmly on the thrust-block. A cotter-pin 7 is arranged in the lower end of 5 the wedge-key for obvious reasons. When it is desired to remove the brake-head, it is only necessary to remove the cotter-pin, drive out the wedge-key, and remove the brake-head 5.

In the form shown in Figs. 3 and 4 the 6 thrust-block is provided with a recess in its front face to accommodate the brake-hanger 8. The top and bottom faces of the thrust-block in this modification are parallel, as are also the edges of the securing-key 6.

In Figs. 5 and 6 I have shown projections 3^a on the top and bottom faces of the thrust-block, around which extend flanges from the brake-head. Through these projections and flanges on the brake-head extend wedge split 7 keys or cotter-pins 6^b, there being two cotter-pins to each head, said cotter-pins being horizontally disposed in this form of my invention, whereas in the forms previously described the securing devices are vertically disposed.

I am aware that minor changes in the construction, arrangement, and combination of the several parts of my beam may be made and substituted for those herein shown and described without in the least departing from the nature and principle of my invention.

Having thus described my invention, what I claim, and desire to secure by Letters Patent, is—

1. In a trussed brake-beam, the combination with a thrust-block having a tapered opening, of a removable brake-head provided with registering openings, and a tapered wedge-key passing through said openings for securing said removable brake-head in position; substantially as described.

2. In a trussed brake-beam, the combination with a thrust-block having inclined 95 faces, of a removable brake-head fitting upon said thrust-block, and a securing device which tends to more firmly seat the brake-head in position; substantially as described.

3. The herein-described thrust-block for 100 brake-beams, the same having a tapered opening for the reception of a brake-head-securing key; substantially as described.

4. The herein-described thrust-block, the

same having tapered faces adapted to be embraced by correspondingly-shaped parts on a brake-head; substantially as described.

5. The herein-described brake-head, the same being provided with rearwardly-extending flanges having tapered faces for embracing a correspondingly-shaped part on which it is seated; substantially as described.

6. The herein-described thrust-block for 10 brake-beams, the same having a recess for a brake-hanger and an opening for the passage of securing means for the brake-head; substantially as described.

7. In a trussed brake-beam, the combina-

tion of a thrust-block and a removable brake-head, one of said parts having an opening and the other of said parts being provided with a registering opening, and a tapered wedge-key passing through said openings; substantially as described.

In testimony whereof I hereunto affix my signature, in the presence of two witnesses, this 10th day of July, 1905.

CHARLES FRANCIS HUNTOON.
